United States Patent Office.

CHARLES W. MOSHER, OF EAST LEON, NEW YORK.

Letters Patent No. 98,992, dated January 18, 1870.

IMPROVEMENT IN LIFTING-JACKS.

The Schedule referred to in these Letters Patent and making part of the same.

To all whom it may concern:

Be it known that I, CHARLES W. MOSHER, of East Leon, in the county of Cattaraugus, and State of New York, have invented a new and improved Wagon-Jack; and I do hereby declare that the following is a full, clear, and exact description thereof, which will enable others skilled in the art to make and use the same, reference being had to the accompanying drawing, forming part of this specification.

This invention relates to improvements in lifting-jacks; and

It consists in a combination, on a platform, of a vertical hollow stand or tube, having a long vertical slot, extending from the platform upward; a vertically moving piston in the said hollow stand, composed of a tube and a rod, adjustable as to length; and a T-headed operating lever and friction-roller, connected to the lower end of the piston, the said roller operating as a movable fulcrum for the lever, which, being worked up and down, will cause the head of the lever to assume either a vertical or horizontal position, thereby raising or lowering the piston on the top of which the weight rests, all substantially as herein specified.

The drawing represents a sectional elevation of my improved jack.

A is the platform or bed, consisting of a strong plank, of wood.

B is the vertical hollow stand, in which a piston,

composed of the rod C and tube D, is arranged to work up and down, and for adjustment on each other for varying the height of the head E, which supports the weight, by means of the pin F passing through the holes G in the tube, and above the top of the rod.

This rod C is jointed, at the lower end, to one end of a T-headed lever, H, working in the slot I, at the bottom of the stand, and having a friction-roller, K, journaled at the other end of the bead, and on which it rolls under the piston, to raise it, when the lever is brought down and from under it; when the lever is raised to let the piston down, the said lever swings on the pivot-joint L, with the piston.

This arrangement provides a very cheap, simple, and durable lifting-jack, applicable for many uses.

Having thus described my invention,

I claim as new, and desire to secure by Letters Patent—

The combination and arrangement of the bed A, hollow slotted stand B, piston C D, pin F, lever H, and roller K, all substantially as specified.

The above specification of my invention signed by me, this   day of   , 1869.

C. W. MOSHER.
